(57) **CLAIM**

The ornamental design for a spray cap for an aerosol container, as shown and described.

DESCRIPTION

FIG. 1 is a perspective view of the top and front of my spray cap for an aerosol container.

FIG. 2 is a elevational view of the front of my spray cap for an aerosol container.

FIG. 3 is a elevational view of a side of my spray cap for an aerosol container; the other side of my spray cap for an aerosol container which is not depicted in the figures is symmetrical with this side view.

FIG. 4 is a elevational view of the back of my spray cap for an aerosol container.

FIG. 5 is a plan view of the top of my spray cap for an aerosol container; and,

FIG. 6 is a plan view of the bottom of my spray cap for an aerosol container.

The broken line showing of the bottom of the spray cap is included for the purpose of illustrating environment only and forms no part of the claimed design.
